UNITED STATES PATENT OFFICE.

HANNIBAL GOODWIN, OF NEWARK, NEW JERSEY; REBECCA GOODWIN
EXECUTRIX OF SAID HANNIBAL GOODWIN, DECEASED.

CAMERA.

SPECIFICATION forming part of Letters Patent No. 700,140, dated May 13, 1902.

Application filed April 22, 1899. Serial No. 714,071. (No model.)

To all whom it may concern:

Be it known that I, HANNIBAL GOODWIN, a citizen of the United States, residing at Newark, in the county of Essex and State of New Jersey, have invented certain new and useful Improvements in Cameras; and I do hereby declare the following to be a full, clear, and exact description of the invention, such as will enable others skilled in the art to which it applies to make and use the same, reference being had to the accompanying drawings, and to characters of reference marked thereon, which form a part of this specification.

The object of this invention is to enable a series of individual films, each of a size to receive a single light impression from the lens, to be stripped from a paper support one after another after having received the impression and be deposited in a dark storage-chamber, each film of the series then being separate from the others, so that when the camera is opened in the dark closet and the films removed no cutting or severing operations will be required preliminary to developing the pictures, fixing, &c.

Further objects are to secure greater compactness of construction in the camera, to reduce the cost of the camera, obtain increased convenience and greater facility in loading, and to secure other advantages and results, some of which may be referred to hereinafter in connection with the description of the working parts.

The invention consists in the improved camera and in the arrangements and combinations of parts of the same, all substantially as will be hereinafter set forth and finally embraced in the clauses of the claim.

Referring to the accompanying drawings, in which like characters of reference indicate corresponding parts in each of the several figures, Figure 1 is a plan of the improved camera. Fig. 2 is a section of the same, taken through line *x*. Fig. 3 is an elevation of the film-holder, a certain platen being removed to show the roller or spool supporting means. Fig. 4 is a detail elevation of the said platen, showing the sliding catches thereon; and Fig. 5 is an edge view of the said platen. Fig. 6 is a plan, and Fig. 7 a longitudinal section, and Fig. 9 a perspective view, showing por-

tions of the series of films employed in the camera; and Fig. 8 is a greatly-enlarged section to show certain cement.

In said drawings, *a* indicates the camera-box, having the usual lens *b* in any suitable arrangement, an open diaphragm *c*, disposed at or near the focal plane of said lens, and a partition *d*, arranged within the camera at right angles to said open diaphragm to form a dark storage-chamber *e* to receive the light-impressed films and store the same away from actinic light-rays until it is convenient to remove said films. A passage *f* leads into said dark chamber from a point behind the open diaphragm, at the upper edge thereof, the said passage being formed by an angle-piece *g*, the upper vertical extension *g'* of which closes the rear end of the dark chamber and the horizontal extension *g''* forms the upper wall of the passage. The sides and bottom of the camera-box and the horizontal extension of the angle-piece *g* project a little—a quarter of an inch, more or less—back of the open diaphragm and at their rear edges receive or form bearings for the separable film-holder *h*, the joint where the parts contact being broken or made impervious to light by a band or lapping-piece *i* or in any other suitable manner. Said film-holder *h* comprises a box-like part adapted to be held to the camera-box by catches *j* or in any other suitable manner, the front plate or platen *k* lying a little back from the open diaphragm *c*, parallel therewith, a space or passage *o* being formed between of sufficient width to permit a free passage for the film and its support between said platen and the open diaphragm, in which passage *o* the film stands in the act of exposure. The lower end or edge of the platen terminates a little short of the bottom of the film-holder to form an open passage *l* for the film as it passes out from the roll or spool *m*, the lower edge of the platen *k* being preferably rounded, as at *n*, to prevent injury to the film.

Back of the platen *k* the film-holder is chambered, the chamber *p* containing the roll or spool *m* and a swinging spool-holder *q* furnishing pivotal bearings for the spool. Said spool-holder comprises a pair of springs *r*, held together by a connection *s* near their

pivotal ends, the said pivotal ends *t* being perforated to receive the pivotal shaft *u*, disposed near the top of the chamber *p*. The lower free ends of the springs provide pivotal 5 bearings for the spool *m* and normally press against the ends of said spool to produce sufficient friction to prevent a premature unwinding of the spool. Upon the removal of the film-holder *h* from the camera-box and 10 withdrawal of the platen *k* from the front of said film-holder the spool-holder at the free ends of the springs can be swung outside of the chamber *p*, where the said free ends can be freely manipulated to insert or remove the 15 spool. When loaded, the spool-holder *q* is simply pushed back into the chamber *p*, when said holder *q* is caught automatically and held in fixed operative position by catches *r*, which engage the outer sides of the springs 20 and both hold said springs from pivotal movement and from spreading, although this latter movement may be also prevented by the side walls of the film-holder, as indicated in Fig. 3.

25 At the upper end of the film-passage *o* is stationed a stripping-blade *w*, adapted to enter behind the free ends of the film as the latter are drawn out from the passage *o* after exposure and detach the said films from the 30 support to which they are secured, as hereinafter described. The said stripping-blade is preferably fastened beneath the angle-piece *g*, projecting down therefrom at an incline away from the passage *f*, as shown in Fig. 2, 35 the lower edge lying near to the outer face of the platen and preferably extending slightly into a recess *k'*, formed near the upper edge of said platen, so that the paper support to which the detachable films are secured will 40 be flexed away from the passage *f* preliminary to a contact with the edge of said blade. Above said blade an out-passage slot *w'* is formed of a width sufficient to receive the 45 paper support. Said slot *w'* is preferably formed in the band or lapping-piece *i*, which is preferably of metal.

At the upper end of the film-holder, preferably upon the band *i*, near the opposite sides of said holder, are secured ears or bearings 33, 50 in which is arranged a drum 4, having at one end a ratchet-and-pawl mechanism 5 of any suitable kind to prevent back movement and at the opposite end a finger-piece 6, by means of which latter the drum 4 may be turned on 55 its axis. Means are provided, such as the hooks 7, for fastening the paper support to the drum, so that when said drum is turned the said paper support will wind on said drum and effect an unwinding of said support and 60 the films thereon from the spool *m*. The tension produced by the friction on the spool *m* keeps the support and films thereon smooth in their passage in the focal plane of the camera.

65 At the top of the camera-box, or at least at one side of the dark chamber *e* thereof, is arranged a removable cover *e'*, which permits

an easy removal of any one of the exposed and stripped films prior to a complete unwinding of the pellicle containing or holding unexposed films. Thus the operator is not compelled to await a complete unwinding of the spool *m*, but can secure a specially-desired exposed film as soon as he can gain access to a dark closet.

To adapt the device more perfectly for daylight loading, I have employed in connection with the dark chamber a friction or drawing wheel 8, adapted to positively draw the light-impressed or exposed films into the dark 80 chamber *e*, and a shutter 11 for closing the dark chamber perfectly against the entrance of light in the event of the removal of the film-holder *h* from the box *a*. The drawing-wheel 8 is shown in Figs. 1 and 2 and is preferably provided with small teeth 9 or other suitable means for producing sufficient friction or holding power of the wheel upon the films as to draw the films positively into the storage portion of the chamber *e*. These 85 teeth 9 are preferably disposed at the opposite ends of the drawing drum or roll 8, and in connection with said teeth I prefer to employ a light spring or springs 10, suitably attached to the adjacent walls of the dark 90 chamber and lightly bearing upon said teeth.

At the inner end of the passage *f* I employ the shutter 11, which closes said passage automatically, preferably by the aid of a light spring 12.

Before the film is detached from its support, as hereinafter described, the forward or upper end of said film is caused to press against the outer side of the shutter *f*, and because of the freedom of movement of the 105 shutter the latter is pressed upon and the film is directed against the roll 8, the said roll being free to turn therewith until the upward push produced by the attached support ceases. After the detaching of the film from 110 its support by the stripping-plate the films, which have been thrust partly into the dark chamber and lie within the passage *f* and on the roller 8, are forwarded into the dark chamber by the said wheel 8 and spring 10. 115 This may be done preliminary to the removal of the film-holder 8 from the camera-box to reload it or for other purposes. I turn the said roll 8 by hand-power from the outside of the box *a*, a suitable finger-piece 13, Fig. 1, 120 being employed for that purpose, when the said films will be rolled forward from the passage *f* and dropped into the dark chamber. The shutter 11 then closes the passage *f* automatically, preventing the entrance of light 125 and permitting the detachment of the film-holder without danger of fogging the light-impressed films within the dark chamber.

The series of films employed is shown in part in Figs. 6, 7, 8, and 9, where 20 indicates a long strip of opaque paper serving as a support for the series of separable films, and 21 21 21 indicate the films attached to one side of the support by cementitious or adhesive matter

22, Fig. 8, of any suitable kind, the said matter being so applied as to permit an easy detachment of the film by the stripping-blade. This may be accomplished by applying the cement 22 to only parts of the film, and the upper or forward edge of the film is not caused to adhere to the backing or support, and thus when said support is turned in its course just prior to its passing over the stripping-blade the partly-detached film will stand out from the support or backing to permit the entrance of the blade between, as will be understood.

Each film of the series is identified both on the film itself and on the backing or support, the serial identifying-marks on the paper coming into sight as the latter is drawn out of the camera, so that the operator may easily know the number of the film at the platen, and thus make a record by number of the view being taken and the identifying-mark on the film enabling the operator to select while in the dark closet any particular view he may wish to withdraw from the collection stored in the dark storage-chamber. The ends of the support 20 extend considerably beyond the ends of the series of films and serve to inclose the films on the spool and protect the same from light while on the market.

30 Having thus described the invention, what I claim as new is—

1. The improved camera, herein described comprising a camera-box, provided with a suitable lens and a film-holder having there-in pay-out roll and stripping means, the said stripping means being arranged to contact with the film, and effect a complete detachment of said film from its support, substantially as set forth.

40 2. The improved camera herein described, comprising a camera-box having an open diaphragm and a dark chamber, the mouth or entrance to which is disposed at or near the plane of said diaphragm, a stripping-blade outside of said mouth or entrance to the dark chamber and a film-holder having a platen and a spool-holder chamber back of said platen, substantially as set forth.

3. The improved camera herein described comprising a camera-box, having a dark chamber and open diaphragm, a stripping-blade, a film-holder separable from the said box and having a platen at the front an out-swinging spool-holder at its free end adapted to be swung out from the spool-holder chamber to permit an easy manipulation of the spool therein, substantially as set forth.

4. The combination with the camera-box *a*, having a dark chamber, an open diaphragm and stripping-blade, of a film-holder adapted to be arranged in connection with said camera-box, the said film-holder having a removable platen adapted to be disposed parallel with the said open diaphragm and form a passage for the film therewith, the said platen terminating at one edge, short of the end of the film-holder to form a passage *l*, for the

film and a spool adapted to be arranged in said film-holder, substantially as set forth.

5. In a camera, the combination with a camera-box having an open diaphragm, a dark chamber above said diaphragm and a stripping-blade, at the top of said diaphragm and adjacent to the mouth of the dark chamber, of a separable film-holder having a platen, adapted to lie parallel to said open diaphragm, said platen being recessed contiguous to the edge of the said stripping-blade to receive said edge and effect a flexing of the film in its passage to said blade, a supply-roller and a draft-roll at opposite ends of said platen, and means for fastening the said film-holder to the camera-box, substantially as set forth.

6. In a camera, the combination with the camera-box, having a dark chamber, open diaphragm, and stripping-blade, of a separable film-holder, having a spool, at the bottom of said open diaphragm and below the stripping-blade and adapted to contain the unexposed portions of the film and a drum above said open diaphragm and stripping-blade and adapted to receive one end of the film and, when turned, to effect an out-passage of the support of the said film and a stripping of the sensitive portion therefrom, substantially as set forth.

7. In a camera, the combination with the camera-box, its dark chamber, open diaphragm and stripping means of a roller for holding the unexposed film, braking means therefor, and a drum or windlass for drawing the film over the said stripping-blade and means for preventing back movement of said drum or windlass, substantially as set forth.

8. In a camera, the combination with the camera-box, its dark chamber and stripping means, of a film-holder separable from said box, having a chamber for the unexposed film and a platen removable from said holder to permit manipulation of the spool-holder, and said spool-holder and means for holding it in place in said film-holder, substantially as set forth.

9. The combination with the camera-box having a dark chamber and stripping-knife, of a spring-actuated shutter for closing said dark chamber automatically and a drawing-in roll arranged within said dark chamber, independent of the shutter, substantially as set forth.

10. The combination with the box, *a*, of a camera, having a dark chamber, of an automatic door at the mouth or entrance to said dark chamber and a drawing-in roll provided with teeth, and a spring for cooperating with said teeth, substantially as set forth.

11. The combination with the camera-box having the dark storage-chamber and stripping means, of a drawing device adapted to grasp the stripped portions after they have been detached and carry them into said dark chamber from the mouth or in-passage thereto, substantially as set forth.

12. In a camera, the combination with a

film-supply spool, a stripping-blade, a platen between said spool and stripping-blade for exposing the films, a take-up spool beyond said stripping-blade for winding up the support or backing, a dark chamber having an entrance into which the stripped portion of the film is forced by the stripping operation an automatic door for said entrance, and means within the dark chamber for entirely drawing in the stripped portion of the film, substantially as set forth.

13. In a camera, the combination with the box having an open diaphragm, dark chamber and stripping-blade at the entrance to said dark chamber, of a film-holder having therein a swinging spool-holder comprising two springs between which the spool is held under friction, substantially as set forth.

14. In a camera, the combination with the box having an open diaphragm, dark chamber and stripping-blade, of a spool-holder consisting of springs providing bearings on which the spool is adapted to rotate, said

springs pressing against the ends of said spool to retard turning, substantially as set forth. 25

15. In a camera, the combination with the box having an open diaphragm, dark storage-chamber for the light-impressed films and a storage-chamber for the unimpressed films and means in the last chamber for holding 30 the films, and the flexible supports therefor, said camera having a platen back of said diaphragm with a film-passage between and at the top of said passage diverging passages, one leading into the dark storage-chamber 35 and the other leading to the exterior of the camera, and stripping means at the junction of the passages, substantially as set forth.

In testimony that I claim the foregoing I have hereunto set my hand this 15th day of 40 April, 1899.

HANNIBAL GOODWIN.
